C. B. Collingsworth

A. D. BENHAM

UNITED STATES PATENT OFFICE.

ARTHUR D. BENHAM, OF JACKSON, MICHIGAN, ASSIGNOR, BY DIRECT AND MESNE ASSIGNMENTS, TO THOMAS J. BIRNEY AND STEPHEN H. CARROLL, OF SAME PLACE, AND SENECA L. BAKER, OF KALAMAZOO, MICHIGAN.

STREET-SIGN.

SPECIFICATION forming part of Letters Patent No. 548,026, dated October 15, 1895.

Application filed July 16, 1894. Serial No. 517,754. (No model.)

To all whom it may concern:

Be it known that I, ARTHUR D. BENHAM, a citizen of the United States, residing at Jackson, in the county of Jackson and State of Michigan, have invented certain new and useful Improvements in Street-Signs, of which the following is a specification, reference being had therein to the accompanying drawings, in which—

10 Figure 1 is a perspective view of my improved sign. Fig. 2 is a perspective view of the lower sign-plate detached. Fig. 3 is a plan view of the supporting-bracket. Fig. 4 is a side elevation thereof, and Fig. 5 is a sectional view.

15 A is the lower sign-plate, preferably of cast-iron, having the lateral flange *a* around the edges on both faces, forming countersunk panels on both sides, on which are formed the 20 raised letters *g*. On the lower edge of the plate in the middle is secured, preferably by being formed integral therewith, the pin *d*, at the top of which is a collar *f*. On top of the plate *A* in the middle is the bracket *L*, terminating in the two separated lugs or lips *P*, between which is formed a socket extending 25 at an angle across the top of the plate. In this socket the tongue *K* on the upper plate *B* is adapted to fit, the two being held together by a transverse pin or bolt *O* entering suitable apertures provided through the parts. The supporting-bracket is formed from a single piece of band-wire doubled on itself in the

middle to form the circular eye *C*. The parallel extension-section *e* and the ends are 35 spread at an angle, as shown at *E*, to form means for securing it to the corner of a building. The bracket being secured in place on a building, the pin *d* of the lower sign is placed in the eye *C* of the bracket, the collar *f* resting 40 on top of the bracket, and the lug *K* on the upper plate is placed in the socket in the top of the lower plate and the two plates secured together. Both sign-plates are thus secured clear from the corner of the building, plainly 45 visible to persons coming in either direction.

The raised letters make it easy to paint the outer faces of the letters of different color from the plate and thus make the sign more easily distinguishable.

50 What I claim as my invention is—

A sign for corners comprising a bracket having a socket in its outer end, a lower sign plate lettered on both sides, a pin in the middle of the lower edge adapted to engage the 55 socket, a lug in the middle of the upper edge having two separated lips to form a transverse socket between, a similar upper sign plate, having a lug on its lower edge engaging the transverse socket, and a pin or bolt 60 passing through the lips and lugs to hold the parts together, substantially as described.

ARTHUR D. BENHAM.
